UNITED STATES PATENT OFFICE.

WILLIAM C. DEVEREAUX, OF DETROIT, MICHIGAN.

DOOR LOCK.

Application filed December 26, 1923. Serial No. 682,782.

To all whom it may concern:

Be it known that I, WILLIAM C. DEVEREAUX, a citizen of the United States of America, residing at Detroit, in the county 5 of Wayne and State of Michigan, have invented certain new and useful Improvements in Door Locks, of which the following is a specification, reference being had therein to the accompanying drawings.

10 This invention relates to locks and latches and refers more particularly to those designed for use upon the doors of vehicle bodies.

15 An object of the invention is to provide a simple and reliable latch that may be locked from the inside of a door upon which it is mounted so that it cannot be unlocked by means of the door handle upon the outside of the door.

20 Another object is to provide a single member for actuating both the latch mechanism and the lock mechanism.

25 Another object is to provide a connection between the actuating member and the locking mechanism whereby the lock mechanism will be rendered inoperative when the latch mechanism is operated from the inside of the door.

30 With the above and other objects in view, the invention consists of certain novel features of construction, combination and arrangement of parts as will be more fully described and particularly pointed out in the appended claims.

35 In the accompanying drawing:—

Figure 1 is a fragmentary rear elevation of a door latch embodying my invention with the cover plate shown in dotted lines;

40 Figures 2, 3, and 4 are cross sections respectively on the lines 2—2, 3—3 and 4—4 of Figure 1.

45 Referring now to the drawing in which like characters of reference designate corresponding parts throughout the several views, the numeral 1 designates a case plate which is secured to the inner side of a vehicle door 2 and which is provided at one edge with a laterally extending flange 3 that is secured to the outer edge of the door.

50 Slidably mounted on the case plate is a bolt 4 having a relatively flat shank 5 extending between a pair of parallel struck-out ears 6 and having an enlarged head 7 extending through the flange 3 for engagement with a keeper 8 upon an upright member 9 of the vehicle body.

The bolt 4 is normally retained in extended position by means of a helical spring 10 having one end thereof rigidly secured between parallel lugs 11 struck out from the case plate 1 and having an arm portion 12 abutting the forward end of a longitudinally extending slot 13 formed in the shank 5 of the bolt.

For retracting the bolt to release the door, 65 I preferably provide a curved lever 14 that is pivoted at its lower end to the case plate 1 and that extends upwardly through the slot 13 and engages an upstanding lug 15 on the upper edge of the bolt. A cover plate 70 16 is preferably arranged parallel to the case plate and is provided with forwardly projecting tongues 17 that extend through openings in the lateral flange 3 and that are preferably riveted thereto. This cover plate 75 is also secured to the case plate by screws 18 that threadedly engage tubular spaces 19 which extend through the case plate 1 and are riveted thereto. The cover plate 16 is provided with an elongated open-ended slot 20 that extends longitudinally thereof and that registers with the bolt, the shank of the bolt being preferably cut away at its inner end as shown at 21 so as to extend beyond the inner end portion of the 80 cover plate.

In order that the bolt may be retracted without moving the lever 14 by a person outside the vehicle body, I preferably provide a rotatable hub 22 that is journaled in 90 the case plate 1 and that has an upstanding actuating arm 23 engageable with a curved arm 24 extending upwardly from the shank 5 of the bolt. The hub 22 is also provided with a polygonal opening 25 that receives 95 the operating shank 26 of a suitable handle 27. Thus, when the arm 23 is rocked by the handle 27 to retract the bolt, the lug 15 on the bolt will be disengaged from the lever 14. Likewise, when the lever 14 is moved 100 rearwardly to retract the bolt the arm 24 will be moved away from the actuating arm 23 so that the handle 27 will remain in normal position.

105 In order that the bolt may be locked in extended position when the door is closed by a person on the inside of the body so that the outside operating handle 27 will be rendered inoperative, I preferably provide a trigger 30 that is pivoted at its inner end 110 upon the case plate 1 and that is provided at its outer end with a recess 31 for receiving

a lug 32 projecting downwardly from the hub 22. Thus, when the trigger is raised, as shown by the full lines in Figure 1, the forward flat face 33 of the lug 32 will engage the flat forward end of the recess 31 so that the hub 22 will be positively held against rotation in a counter clockwise direction. Inasmuch as the upstanding arm 23 of the hub is normally in engagement with the flange 3 of the case plate the hub 22 will also be held against rotation in a clockwise direction.

In order that the lever 14 may be used to actuate the trigger 30, I preferably locate the pivot 35 for the trigger in rear of the pivot 36 for the lever and provide an extension 37 that projects from the lever at a point below the pivot 36 and that is adapted to engage a curved extension 38 that projects upwardly from the trigger 30 preferably at a point in the rear of the pivot 35. Thus, when the lever 14 is moved forwardly to lock the bolt the extension 37 will engage the extension 38 and will cause the forward end of the trigger 30 to be swung forwardly so that the recess 31 will receive the lug 32. For normally retaining the lever 14 in neutral position, I preferably provide a spring 39 that is coiled about one of the spacers 19. One end of the spring 39 abuts the forward edge of the lever 14, while the other end is preferably held by a bent over lug 40 on the case plate 1.

The lever 14 is also used to release the bolt and for this purpose, I preferably provide an upstanding lug 41 on the upper edge of the trigger 30 in advance of the pivot 35 so that when the lever 14 is moved rearwardly the extension 37 will engage the projection 41 and will cause the forward end of the trigger to be swung downwardly so that the lug 32 will be disengaged from the recess 31. Thus, when the bolt is locked the lever 14 may be moved rearwardly initially to release the trigger to unlock the bolt and then may be moved further in a rearward direction to retract the bolt and release the door while maintaining the locking mechanism inoperative.

While it is believed that from the foregoing description, the nature and advantages of the invention will be readily apparent I desire to have it understood that I do not limit myself to what is herein shown and described and that such changes may be resorted to when desired as fall within the scope of what is claimed.

What I claim as my invention is:—

1. In a lock, the combination with a case plate and a movable bolt on the case plate, of a rotatable member on the case plate adapted to actuate the bolt, a trigger on the case plate for holding said rotatable member against movement, an extension on the trigger, a projection on the trigger, and a lever

having an extension alternately engageable with the extension and projection aforesaid to move said trigger into and out of locking engagement with said rotatable member.

2. In a lock for doors and the like, the combination with a spring pressed bolt, and means operable from one side of the door for retracting the bolt, of means for rendering the retracting means inoperative having spaced projections, and means operable from the inside of the door for retracting the bolt, said inside retracting means being movable in opposite directions to alternately engage the projections of the second means for moving the latter to operative and inoperative position.

3. In a latch for doors and the like, the combination with a spring pressed bolt, and means operable from the outside of the door for retracting the bolt, of a locking member engageable with a portion of the outside operating means for rendering the same inoperative, and means operable upon the inside of the door of retracting the bolt, said inside operating means having an extension alternately engageable with different portions of the locking member to actuate the same, said inside operating means being movable in one direction to actuate the locking member into locking engagement with the outside operating means, and being movable in the opposite direction to release the locking member and subsequently retract the bolt.

4. In a lock for doors and the like, the combination with a spring pressed bolt, and means upon the inside of the door for retracting the bolt, of a hub operable from the outside of the door having an arm for retracting the bolt, a projection on said hub, and a member adapted to be moved by the inside retracting means into and out of engagement with said projection for alternately locking and releasing said arm.

5. In a lock for doors and the like, the combination with a spring pressed bolt, and means upon the inside of the door for retracting the bolt, of a hub operable from the outside of the door having an arm for retracting the bolt, a projection on said hub, and a member pivoted below the inside operating means adapted to be engaged directly by a portion of the inside operating means to be alternately moved into and out of engagement with the projection on the hub for alternately locking and releasing the latter.

6. In a lock for doors and the like, the combination with a spring pressed bolt, of a lever operable from the inside of the door for retracting the bolt, a hub having an arm operable from the outside of the door for retracting the bolt, a projection on the hub, a locking member adapted to be moved alternately into and out of locking engage-

- ment with the projection, and a projection on the lever alternately engageable with different portions of said member for moving the same into and out of locking engagement with the first projection.
7. In a latch for doors and the like, the combination with a spring pressed bolt, and means operable from the outside of the door for retracting the bolt, of a locking member engageable with a portion of the outside operating means for rendering the same inoperative, and pivoted means operable upon the inside of the door for retracting the bolt, said inside operating means having an extension beyond the pivot for actuating the locking member, said inside operating means being movable in one direction to actuate the locking member into locking engagement with the outside operating means and being movable in the opposite direction to release the locking member and subsequently retract the bolt.
8. In a lock for doors and the like, the combination with a normally projected bolt, of a hub operable from the outside of the door having an arm for retracting the bolt, a projection on the hub, a member engageable with the projection for rendering the arm inoperative, and a pivoted member operable from the inside of the door for retracting the bolt having a projection beyond the pivot for actuating the member aforesaid.
9. In a lock for doors and the like, the combination with a normally projected bolt, of a hub operable from the outside of the door having an arm for retracting the bolt, a projection on the hub, a pivoted member engageable with the projection for rendering the arm inoperative, a pivoted lever operable from the inside of the door for retracting the bolt having a projection

adjacent to its pivot for actuating the member aforesaid.

10. In a lock for doors and the like, the combination with a normally projected bolt, of a hub operable from the outside of the door having an arm for retracting the bolt, a projection on the hub, a pivoted member engageable with the projection, said member having spaced projections, and a pivoted lever operable from the inside of the door having an extension beyond its pivot alternately engageable with said projections for moving said member to operative and inoperative positions.

11. In a lock for doors and the like, the combination with a case plate, and a normally projected bolt carried thereby, of a hub operable from the outside of the door having an arm for retracting the bolt, a projection on the hub, a member operable from the inside of the door for retracting the bolt, a member pivoted on the case plate below the bolt adapted to engage the projection on the hub for rendering the arm inoperative, and a projection on the last retracting member for actuating said pivot member.

12. In a lock for doors and the like, the combination with a normally projected bolt, of a hub operable from the outside of the door having an arm for retracting the bolt, a projection on the hub, a member operable from the inside of the door for retracting the bolt, and a member located below the bolt adapted to be moved by the last retracting member into and out of engagement with the projection of the hub for alternately holding and releasing said arm.

In testimony whereof I affix my signature.

WILLIAM C. DEVEREAUX.
